DESIGN FOR A DISPLAY CONTAINER

George L. Rosenfeld, Cleveland, Ohio

Application August 22, 1940, Serial No. 94,551

Term of patent 3½ years

To all whom it may concern:

Be it known that I, George L. Rosenfeld, a citizen of the United States, residing at Cleveland, in the county of Cuyahoga and State of Ohio, have invented a new, original, and ornamental Design for a Display Container, of which the following is a specification, reference being had to the accompanying drawing, forming part thereof.

I claim:

The ornamental design for a display container, substantially as shown.

GEORGE L. ROSENFELD.
